DRINKING CUP

Myron M. Levin, Lincolnwood, and Norton R. Sachnow, Wilmette, Ill. (both of 4315 N. Lincoln Ave., Chicago, Ill. 60618)

Filed May 18, 1966, Ser. No. 2,344

Term of patent 14 years

(Cl. D44—9)

FIG. 1 is a side elevational view of a drinking cup showing our new design;

FIG. 2 is a front elevational view;

FIG. 3 is a reduced scale top plan view; and

FIG. 4 is a sectional view on line 4—4 of FIG. 3.
We claim:

The ornamental design for a drinking cup, as shown.
